United States Patent

Des. 238,056
Patented Dec. 16, 1975

238,056

SPIRIT LEVEL INCLINOMETER

Jack B. Foster and Jack E. Antes, Santa Ana, Calif.,
assignors to Super Seer Corporation, Evergreen, Colo.

Filed Sept. 10, 1973, Ser. No. 396,005

Term of patent 14 years

Int. Cl. D10—04

U.S. Cl. D10—69

Fig. 1

Fig. 2

Fig. 3

Fig. 4

FIG. 1 is a front perspective view of a spirit level inclinometer showing our new design;

FIG. 2 is a right end elevational view thereof;

FIG. 3 is a top plan view thereof; and

FIG. 4 is a front elevational view thereof, the rear being identical therewith.

We claim:

The ornamental design for a spirit level inclinometer, substantially as shown and described.
